(57) **CLAIM**

The ornamental design for hand-held massager, as shown and described.

DESCRIPTION

FIG. 1 is a left side elevation view of a hand-held massager, a right side elevation view of the massager being a mirror image thereof.

FIG. 2 is a front elevation view of the massager of FIG. 1, a rear elevation view of the massager being a mirror image thereof; and,

FIG. 3 is an isometric view of the massager of FIG. 1. The broken lines illustrate environmental structure that form no part of the claimed design.
